UNITED STATES PATENT OFFICE.

VICTOR M. ALLEN, OF WAVERLY, NEW YORK.

WINDOW VENTILATOR.

Application filed August 14, 1920. Serial No. 403,568.

This invention relates to window ventilators and has for its object the provision of a device which may be set in a window frame below either sash and easily adjusted to admit a desired volume of air or to exclude all outside air and prevent the entrance of rain, snow, or other elements.

Another object of the invention is to provide means whereby when the ventilator is opened, guards will be provided to prevent side drafts and to screen the occupants of the room from observation from the outside.

Other objects of the invention are to provide means to prevent spreading of the panels and the frame in which they are mounted; to house the working parts within the frame, so that they will be protected against breakage, and to provide an adjusting mechanism which will be simple and direct acting.

Other incidental objects will appear in the course of the following description.

A preferred embodiment of the invention is illustrated in the accompanying drawings in which—

Fig. 1 is an elevation of my improved window ventilator viewed from the inside and in closed position;

Fig. 2 is a plan view of the same;

Fig. 3 is an enlarged vertical section with the panels in partly open position;

Fig. 4 is an enlarged end elevation of the closed ventilator;

Fig. 5 is a detail section of a part of the adjusting mechanism;

Fig. 6 is an enlarged detail section showing the manner of connecting a panel to the adjusting shaft;

Fig. 7 is a detail of the stay rod;

Fig. 8 is a section on the line 8—8 of Fig. 1; and

Fig. 9 is an enlarged transverse section of the upper portion of the ventilator showing the closed relation of the panels.

The ventilator comprises a frame 1, which is adapted to fit in a window between the sash stops or beads thereon; it may be placed below the raised lower sash with the sash resting thereon or it may be placed in the outer grooves below the upper sash, in which event the lower sash may be raised or lowered at will without requiring any shifting of the ventilator. One end strip of the frame may be adjustable longitudinally of the frame so as to adapt the device to windows of different widths and this

strip may be secured in a set position by a thumb screw 2. The frame may be provided on its top side or edge with a metal cover 3, adjustable transversely and secured in adjusted position by set screws 4 passing through transverse slots 5, the frame being thus adapted to fit under sashes of various widths, and to allow of its extension in towards the room, to come under the lower sash, when the ventilator is set in between the stops that hold the upper sash. This to prevent the storm from coming in between the ventilator top and the bottom of the lower sash when raised, the flange coming up on the inside of the bottom of the lower sash the same as when the ventilator is set directly under the lower sash. The cover is provided along its inner edge with an upstanding flange 6, which is adapted to engage against the sash and prevent the entrance of water under the same. The frame is rectangular to rest securely in the window frame and upon the sill and presents a central opening in which the ventilating panels 8 are mounted.

The panels 8 are oblong strips of transparent or translucent glass or other material carried in metal holders 9, which receive the ends of the strips and extend across their lower edges so as to firmly support the same. The holders project above the upper edges of the panels, as at 10, to form fulcrum lugs or ears through which pivot or fulcrum screws or pins 11, are inserted into the frame to secure the panels in place. The space between the holders over the upper edge of a panel is open to facilitate the removal of a broken panel and it will be readily understood that the heads of the pivot screws serve as retainers to prevent the panels being accidentally released from the holders. To further facilitate the withdrawal of a broken panel and the insertion of a new panel, the wooden guard strips 12 on the inner side of the frame are secured in position by screws so that they may be easily removed and replaced. These strips, when in position, prevent rain or other weather elements beating around the ends of the panels into the room. The holders for the intermediate panels are cut away on their outer faces at their upper ends, as shown at 13, and on their inner faces at their lower ends, as shown at 14, so that the panels may be in intimate contact when closed as shown in Fig. 9, and

form a wind and dust-proof joint. As will be readily understood, the holder for the bottom panel is cut away on only its front face while the holder for the top panel is cut away on only its rear face.

In the lower edge of the top bar of the frame I form a groove or longitudinal chamber 15 having an upturned rib or flange 16 along the edge of its front wall and on the upper edge of the top panel I provide an overhanging hook-like lip or flange 17 which extends into the recess 15, and is adapted to engage upon the rib 16 so that the weather elements can not work over the top of the panel and into the room, as will be readily understood on reference to Fig. 9. The overhanging lip is carried on a base plate 18, which is fitted snugly upon the top edge of the upper panel, as shown clearly in Figs. 3 and 9, and the holders 9 for said panel are expanded at their upper ends, as at 19, to accommodate the base plate and lip and hold them snugly on the panel.

One of the panels is carried by a pivot rod 25 instead of the screws 11, said rod extending through the upper extremities of the holders and being journaled in the side members of the frame. Rivets or similar fastenings 21 are inserted through this rod 25 and the inner webs of the holders to secure the rod to the holders and these holders are enlarged, as at 22, so as to be sufficiently reinforced to sustain the strain of turning the panels. A worm pinion 24 is provided on one end of the rod 25 and meshes with a worm 23 on a shaft 20 which is housed within the end of side bar of the frame and equipped at its free end with a milled knob or other form of handle 26', whereby a turning movement may be imparted to rod 25 to adjust the panels. It will be readily understood that the turning movement of the pivot rod or shaft 25 shifts the angular positions of the panels so as to open the ventilator to a greater or less degree.

To effect simultaneous movement of all the panels, connecting bars 26 are provided at the ends of the panels and the panels are pivoted to this connecting bar by pins or studs indicated by dotted lines at 27, the pins or studs being spaced apart the same distance as the pivotal connections of the panels with the frame so that the swinging movement of one panel will be transmitted through the connecting bar to all the panels. The panels will be held in the set position by the well known braking action of the worm gearing. The connecting bars 26 are relatively thin and may be of sheet material but they should obviously be long enough to connect all the panels; they are preferably of such width that their inner edges will rest against the facing guard strips 12 and their outer edges will lie flush with the outer side of the frame when the

ventilator is closed. The connecting bars are provided near their ends with arcuate slots 28 which play over pins 29 on guard plates 30 of similar dimensions as the connecting bars and arranged between said bars 70 and the sides of the frame. The guard plates 30 are provided near their ends with arcuate slots 31 playing on studs or pins 32 on the end strips of the frame.

The holders 9 for the lowermost panel are extended somewhat below the lower edge of the panel and a tie rod 33 is fitted at its ends in said holders and is secured to the same by rivets or similar devices 34, as shown. Spreading of the holders and consequent release of the panel is prevented by the provision of the tie rod and, as the pivots 27 are headed studs, the connecting bars will be prevented from falling away from the panels.

From the foregoing description, taken in connection with the accompanying drawings, the operation and advantages of the device will be readily understood and appreciated. When set in a window with the panels set as in Fig. 3, passages through which fresh air may flow into a room are provided and it will be noted that the air currents must flow upward so that dust will drop to the outside of the window and the air passing into the room will be substantially free of impurities and air currents moving upwardly will not make a draught to blow articles about the room or cause colds. To set the panels at any desired inclination, the shaft 20 is turned by manipulation of the handle 26', and the fulcrum rod 25, will be rotated or rocked through the gearing shown and described. As this rod is connected rigidly with the adjacent panel holders, the panel, will, of course, swing as the rod rocks and the connecting bars 26 will transmit the motion to the other panels so that all the panels will assume the same inclination. As the panels swing outwardly, 10 the connecting bars 26 also, of course, swing outwardly and ride upon the studs or pins 29 until the ends of the slots 28 impinge against the same whereupon a pull will be exerted upon said studs or pins to draw the 11 guard plates 30 outward so that the bars and plates together form guards or shields to prevent lateral air currents entering the ventilator and to screen the occupants of the room from the view of persons standing at the side of the window. If the panels be swung inwardly the connecting bars and guard plates will telescope into the spaces between the ends of the panels and the adjacent end strips of the frame with their outer edges flush with the outside of the frame so as to present a neat appearance. Thus the side guards extend and close only so far as the panels are opened or closed. The device is simple in construction and 12

efficient in use, serving the purposes of an awning, a window and a ventilator.

Having thus fully described my invention, what I claim as new and desire to secure by 5 Letters Patent of the United States is—

1. In a window ventilator, the combination of a frame having a longitudinal recess in the under side of its top bar and provided with an upturned longitudinal rib on the 10 front wall of said recess, a plurality of panels pivotally mounted in the frame, the pivot of one of the panels being elongated, a worm wheel fixed on said elongated pivot, a shaft disposed transversely to the worm 15 wheel, means for setting said shaft, a worm on said shaft meshing with the worm wheel, and an overhanging lip extending along the top of the uppermost panel and playing in the recess in the frame to engage over and 20 bear upon the upturned rib.
2. In a window ventilator, the combination of a frame, a series of panels pivotally mounted in the frame, means connected with one of the panels for setting the same, connecting bars pivotally connected to the 25 panels whereby to effect synchronous movement of the panels, said connecting bars having arcuate slots, studs on the frame, guard plates having arcuate slots engaging 30 said studs, and studs on the guard plates fitting in the slots in the connecting bars.
3. In a window ventilator, the combination of a frame, a plurality of holders pivoted at their upper ends in the frame, panels

having their end edges engaged in said holders, connections between the holders, means acting on one panel to set the same, and a tie bar disposed below the lower edge of one panel and having its ends secured in the 35 holders carrying said panel.

4. In a window ventilator, the combination of a frame, holders having open tops, panels fitted at their ends in the holders with their top edges below the upper ends of the holders, and pivots extending through 40 upper ends of the holders into the frame, and bearing on the upper edges of the respective panels, whereby to pivotally attach the 45 holders to the frame and retain the panels in the holders.

5. In a window ventilator, the combination of a frame, holders having open tops, panels fitted at their ends in the holders with their top edges below the upper ends of the 50 holders, and pivots extending through upper ends of the holders into the frame and bearing on the upper edges of the respective panels whereby to pivotally attach the 55 holders to the frame and retain the panels in the holders, the pivots of one panel extending entirely across the panel and being pinned to the inner webs of the holders and 60 said webs being enlarged to reenforce the fastening.

Signed at Waverly, New York, this fif- 65
teenth day of March 1920.

VICTOR M. ALLEN.
